DOCKING LIGHT INSTALLATION FOR
MARINE CRAFT

John F. Morse, Hudson, Ohio

Application March 12, 1949, Serial No. 81,162

4 Claims. (Cl. 240—26)

1

The present invention relates to improvements in the construction and installation of lights especially adapted and intended for craft of the power operated type. This invention is in the nature of an improvement in the Marine Docking Light shown in my prior application, Serial No. 62,680 filed November 30, 1948, now Patent No. 2,593,171, and is especially designed to improve the method of mounting lights of the character shown and described therein.

These lights are especially designed for mounting in the hull of the boat below the deck and usually on either side of the prow of the boat in such position that the rays from the lights will illuminate the surface of the water ahead and at the sides of the boat without causing objectionable reflections from the surface of the deck. These objects and advantages are more particularly set out in the said prior application.

The object achieved by the present invention is to simplify and improve upon the method of mounting the docking light in the hull of the boat. One of the difficulties experienced in mounting the lights in the hull of the boat is due to the fact that the hull of the boat is almost always curved, usually in both directions, at the points where the lights were most advantageously situated, which is well toward the prow of the boat and below the rub rail. In my former application the curvature in the hull of the boat was compensated for by the making of a wood adapter block which would be fitted to the inner curved surface of the hull and provided on its inner side with a flat surface against which the flange of the holder or frame would rest. The curvature on the outside of the hull was taken up by a flexible clamping plate or ring which was conformed to the curvatures of the hull by drawing up on bolts which secured the assembly to the hull.

While the method of my former application was satisfactory for the purpose, the matter of shaping the adapter block to the interior of the hull so as to fit the curvature of the inside of the hull presented practical difficulties.

It is therefore an object of the present invention to provide for a new type of mounting which will make the task of installing these docking lights easier, simpler, and more efficient. The installation is always water tight and the directions for installations are easy to follow with unusually satisfactory results.

Briefly stated the improvement consists in the employment of a cement block or base for the light which will not only readily adapt the assembly to the curvature of the boat and thus make

2

the operations of installation much easier, but the completed job will be more satisfactory in other ways.

The drawings show the installation as finally completed and also an intermediate step which will illustrate the procedure which is followed. While the present disclosure represents the best known and preferred method of installing the new form of light mountings, it is subject to modifications and changes within the scope of the invention as set forth in the appended claims.

In the drawings, in which the preferred embodiment of the invention is disclosed:

Fig. 1 is a side elevation looking at the prow of the boat showing the location of one of a pair of lights installed at a preferred location.

Fig. 2 is a cross-section through the installation as it is completed on the broken line 2—2 of Fig. 1.

Fig. 3 is a side elevation partly in section taken in the location of Fig. 2, showing an intermediate step in the installation of a light.

Fig. 4 is an enlarged view taken on the line 4—4 of Fig. 1 looking at the installation from above and inside the hull.

In the drawings the numeral 1 indicates the hull of a boat equipped with the improved docking light. In equipping a boat with the light, the owner selects a location well toward the prow and in a position so that the rays of light will illuminate the water as described in my aforesaid application. At almost any point which may be selected, the hull of the boat has curvatures in both directions and the problem arises of fitting the light so that the installation will not only be neat and attractive but also will be water tight. In the installation of these lights in the manner set forth herein, it is desirable to select, if possible, a location where it will not be necessary to cut any of the ribs or battens on the interior of the hull.

In the form shown and described herein the docking light as a whole is given the numeral 5. It is preferably oval in shape with the long axis of the oval extending fore-and-aft. The light is composed of a main frame 6 having a vertical rim or wall 7 of a height to extend well into an opening 4 cut in the hull and to the interior of the hull where it has an outwardly extending peripheral flange 8 which is spaced from the inner surface of the hull. On the underside of the flange 8 is an inwardly extending rib or lip 9, the purpose of which will appear.

Internally the frame is formed with a conical socket portion 10, the axis of which is located at

about 20 degrees to the plane of the frame so that the rays of light will be projected at the best angle to illuminate the water at the side of and head of the boat. At the base of the socket the frame is provided with a flanged portion 12, the inner surface of which is provided with a curved seat 14 to receive the spherical lamp housing indicated at 15. The details of the interior of the lamp housing are not important to the present invention and therefore have been omitted. The lamp housing is held in its adjusted position on the seat 14 by a clamp ring 18 which is held by bolts 19 passing into threaded sockets in the flange 12. A gasket 20 in the space between the lamp housing and the clamp ring and flange 12 makes a water-tight joint at this point.

The rim 7 of the frame 6 projects outwardly of the hull for a short distance, as shown in Fig. 2, and around this projecting portion of the frame is placed the oval-shaped clamping plate or ring 25, the inner periphery of which fits closely around the projecting portion of the frame and the underside of which fits against the hull.

Because the hull of the boat is usually on a curve, both fore-and-aft and also in a vertical plane, a rigid clamp plate would not fit against the outside of the hull but would leave large gaps around the ring which would not only be unsightly but would make it difficult to have the hull water-tight at this point. To compensate for this compound curvature, the ring 25 is made of a material which will allow it to bend sufficiently so that when the docking light is completely installed, the inner surface of the ring will conform to the curvature of the outside of the hull and bear tightly against it all around the light. The clamp ring is therefore made of a ductile metal or it may be made of a plastic material, if desired. To increase the ductility of the ring, it may be hollowed out at intervals as shown at 26.

To hold the frame and clamp ring in position, securing bolts 28 are passed at intervals through holes 27 in the flange 8, through holes 31 in the hull, and into the clamp plate, the heads of the bolts bearing against the outer surface of the clamp ring 25 and the nuts 29 against the inner surface of the flange 8. Ten of these bolts 28 are shown spaced at equal distances about the assembly.

Threaded in the flange 8 and bearing against the inner surface of the hull are supplemental bolts known as leg screws, indicated by the numeral 30. Four of these leg screws are distributed about the frame. Their function is to act as spacing means for holding the frame in position while the cement backing is put in place.

In the completed installation, a foundation or backing of cement fills the space bounded by the flange 8, the rim 7, and the inside of the hull. This backing is indicated by the numeral 32. As shown in Fig. 2 the backing lies within the rib 9 on the flange 8 and this serves to hold the cement block in position, interlocking therewith so that if the block should crack pieces will not be dislodged from the light.

For the purpose it is preferred to use a high strength gypsum cement which will set rather quickly but can be applied to the space by hand, and packed and smoothed therein, in a sufficient interval before setting so that the installation may be made properly before the cement sets and hardens. Mixed with water, cements of

this type acquire a putty-like consistency and may be formed, packed and shaped by hand.

The method of installing the light will now be described:

- 5 The purchaser of a light is furnished with a template which shows the outline of the opening 4. Using the template as a guide, he cuts the hole 4 in the hull of the correct size so that the frame 6 will fit therein as accurately and 10 closely as possible. He then disassembles the light, removing all of the bolts and screws from the frame and removing the clamp ring 18 and the lamp housing 15. He then places the frame 6 in reverse position in the hole 4, with the flange 8 on the outside of the hull, and uses the holes 27 as location marks for making the holes 31. He now removes the frame 6 and inserts the leg screws 30 to a depth as closely as possible approximating the distance which the flange 8 will be from the inner surface of the hull. He now 20 passes the frame through the hull and reinserts it from the rear until the ends of the leg screws 30 come in contact with the inner surface of the hull, so that the rim 7 projects through the hole 4 a distance approximating the thickness of the clamp ring 25. Due to the curvature of the hull, the rim will not extend through equally at all points around the opening 4, but the maximum extension should exceed the thickness of the 30 clamp ring only sufficiently to compensate for the curvature of the hull. The leg screws will be adjusted to the correct distance at this time.

After these adjustments have been made and the frame is resting evenly on all four leg screws, 35 the frame is held firmly in place and the extending portion of the ring and the crack between the hull and the frame is filled with a seam compound indicated by the numeral 35. The back of the clamp ring is then liberally coated 40 with the seam compound and is placed in position around the extending portion of the rim. The heads of the bolts 28 are likewise coated and the bolts are then inserted in position and the nuts 29 are applied to their inwardly projecting 45 ends. The nuts on the front center and rear center bolts 28 are drawn down with considerable force so that the clamp ring assumes the fore-and-aft curvature of the hull, although it may not fit the hull closely at this time. The 50 nuts on the other bolts are drawn down lightly.

The installation is now in the condition shown in Fig. 3 and after making the final checks and 55 adjustments to see that the elements are all properly located, the operator is ready to apply the cement backing. The cement, being mixed and having reached the proper consistency, is forced into the space which it is to occupy, care being taken to fill all of the space and all of the crevices. As the cement starts to harden the outer surface is smoothed off.

After the cement has set, all of the nuts 29 are tightened evenly and in rotation about the frame which brings the clamp ring down snugly against the outside of the hull. Any excess seam compound may be removed, care being taken to see that the cracks and crevices on the outside of the hull are thoroughly caulked. The lamp housing may now be mounted in place and the installation is complete.

While the construction and procedure of installation has been given in detail, these details may be varied if desired. However, by following the instructions a thoroughly satisfactory installation may be made and the light will be completely water-tight and will make a pleasing ad-

dition to the appearance of the boat. If the leg screws project too far into the interior of the boat the projecting heads may be cut off, but ordinarily this is not necessary.

What is claimed is:

1. In combination with a curved boat hull having an opening therethrough, a docking light for installation in said opening, said light having a frame removably fitted within said opening and extending on either side of the hull, a flange on the inner side of the frame spaced from and overlying the hull, a cement base filling the space between the flange and the inside of the hull, a flexible clamp ring surrounding the outwardly projecting portion of the frame and bearing against the outside of the hull, and bolts extending from the flange through the hull and clamp ring conforming the clamp ring to the outer curvature of the hull and holding the frame in position on the hull.

2. In combination with a curved boat hull having an opening therethrough, a docking light for installation in said opening, said light having a frame removably fitted within said opening and extending on either side of the hull, a flange on the inner side of the frame spaced from and overlying the hull, spacing means to hold said flange at a fixed distance from the hull, a cement base filling the space between the flange and the inside of the hull, a flexible clamp ring surrounding the outwardly projecting portion of the frame and bearing against the outside of the hull, and bolts extending from the flange through the hull and clamp ring conforming the clamp ring to the outer curvature of the hull and holding the frame in position on the hull.

3. In combination with a curved boat hull having an opening therethrough, a docking light for installation in said opening, said light having a frame removably fitted within said opening and extending on either side of the hull, a flange on the inner side of the frame spaced from and

overlying the hull, set screws threaded through said flange and bearing on the hull to fix the distance between the flange and the inside of the hull, a cement base filling the space between the flange and the inside of the hull, a flexible clamp ring surrounding the outwardly projecting portion of the frame and bearing against the outside of the hull, and bolts extending from the flange through the hull and clamp ring conforming the clamp ring to the outer curvature of the hull and holding the frame in position on the hull.

4. In combination with a curved boat hull having an opening therethrough, a docking light for installation in said opening, said light having a clamp ring surrounding the outer edge of said opening, a frame removably fitted within said opening and clamp ring and extending inwardly beyond the inside of the hull, a flange on the inner side of the frame spaced from and overlying the hull, set screws threaded through said flange and bearing on the inside of the hull to space the flange therefrom, a cement base filling the space between the flange and hull, and bolts extending through the hull around the opening and clamping the flange to the ring.
